F. T. COSTELLO

PLUNGER PUMP

Filed March 17, 1924

Inventor
FRANK T. COSTELLO

Attorney

UNITED STATES PATENT OFFICE.

FRANK T. COSTELLO, OF VACAVILLE, CALIFORNIA, ASSIGNOR TO STANDARD SPRAY PUMP COMPANY, A CORPORATION.

PLUNGER PUMP.

Application filed March 17, 1924. Serial No. 699,957.

This invention relates to plunger pumps of the cam or eccentric operated variety and has for its principal objects a pump of this kind especially suitable for use in pumping chemical sprays for fruit trees, etc., and which will stand up to the heavy duty and continuous operation to which these pumps are subjected.

My improvements are shown in the drawings accompanying this specification and wherein Figure 1 is a vertical section along the center line of my pump, showing all of its important elements, and Figure 2 is a side view of the pump showing the rolling cam arrangement in section.

In the figures, (1) is a main body casting, (2) a bronze cylinder lining having a flange (3) bolted to the upper edge of the body casting as shown.

Opening to the lower part of the cylinder are suction and discharge ports (4) and (5) having suction and discharge valves (5') and (6) thereon, and over each valve is a cover plate (7) having one end slipped under a notch (8) in the casting and the other end bolted down by a bolt (9) engaging slots in both members for ease of removal, for gaining access to the valves.

Within the bronze liner (2) is a plunger (10) having a cup washer (11) at its lower end.

The plunger is elongated to provide a substantial guiding surface against lateral motion, and extending through it is a rod (12) shouldered at (13) and bolted to it by the nut (14).

The upper end of the rod bears a plate (15) preferably hardened on its upper surface and below the plate is an expanding spiral spring (16) reacting against the upper flange (3) of the liner (2), and which normally forces the plunger upward to operate the suction of the pump.

The downward or power stroke is effected by the action of a rolling eccentric ring (18) actuated by a shaft (19) having an eccentric (20) formed thereon surrounded by a roller bearing (21) within the ring (18).

The eccentric (20) on the shaft in revolving forces the ring (18) up and down to 50 actuate the plunger and in doing so the ring rolls back and forth on the surface of the plate (15).

Figure 2 shows the opposite section of this cam ring arrangement with the parts described similarly numbered and also shows a flange (22) at each end of the ring for retaining the roller bearing in place within it and forming an enclosed grease or oil housing for the rollers. These flanges are 60 pressed tightly into the ring and fit close to a shoulder (23) around the cam thus preventing displacement of the ring.

At (24)—(24) are indicated the usual roller separators or cage, and at (25) in one 65 or both flanges is an oil plug or screw for removal to fill the bearing with oil or grease.

Bearings (26)—(26) on the main body casting at both sides of the eccentric revolvably support the shaft (19), which latter 70 is rotated by any of the usual means not shown as not being involved in the invention.

I am aware of cam and eccentric driven plunger pumps of this general type, but do 75 not know of any having the improved features of my pump including the enclosed roller bearing, self-lubricating rolling ring, doing away with the destructive wiping action of cams and heretofore making it necessary to run such pumps with the cam surfaces submerged in oil.

I claim:

In a pump, having a cylinder, a reciprocating piston in said cylinder and a piston rod, secured to said piston, a resiliently mounted plate secured transversely to the outer end of said piston rod, a revoluble ring whose periphery contacts with the outer face of said plate, a rotatable shaft transverse to said rod, an eccentric fixedly secured to said shaft and disposed within said ring, a series of rollers between the eccentric and the inner periphery of the ring and contacting with both.

FRANK T. COSTELLO.
